UNITED STATES PATENT OFFICE

FREDERICK D. REYNOLDS, OF ST. LOUIS, MISSOURI

HEEL PLATE CLAMP

Application filed January 15, 1931. Serial No. 508,945.

This invention relates to new and useful improvements in heel plates.

The particular type of heel plates to which this invention appertains is substantially of crescent shape having a curved intermediate portion and divergent ends. As it is not practicable to make heel plates in a plurality of sizes to fit heels of shoes of various sizes, the heel plates are generally made in one size with the end portions occupying outermost positions, whereby said heel plates can be fitted to heels of large sized shoes. To fit said heel plates to heels of smaller sized shoes, the general practice is to subject the end portions of the plate to pressure so as to contract said plate and reduce the span between the ends thereof. The common practice has been to place one end of the plate on a suitable support and tap the other end with a hammer. This method is unsatisfactory as the intermediate portion of the plate has a tendency to buckle, thereby distorting said plate and no means are provided to gauge the extent of contraction. It is the object of the present invention to provide a device whereby the heel plate can be clamped in position and the intermediate or curved portion thereof held against distortion while the end portions are contracted to proper shape.

Other objects of the invention are to provide a pair of clamping members between which said heel plate is secured with the ends thereof exposed so that the latter can be placed under pressure to contract the same; said plates being provided with interlocking pins and apertures and said pins traversing apertures formed in the intermediate portion of the heel plate so as to hold the latter in proper position during the contraction operation.

Further objects of the invention are to provide a pair of clamping members for securing therebetween the heel plate, the ends of said heel plate projecting beyond said plates and the latter being provided with suitable indicia cooperating with said projecting ends to indicate the extent of the span of said ends relatively to the various sizes of shoes.

Still other objects of the invention are to provide a novel method of adjusting heel plates which consists in clamping the intermediate portion of a heel plate between a pair of plates, interlocking with each other and with said plate, and then subjecting the exposed ends of said plate to pressure to contract the same in accordance with the marks arranged on one of said plates.

With these and other objects in view, my invention consists in certain novel features of construction and arrangement of parts hereinafter more fully described and claimed, and illustrated in the accompanying drawings, in which—

Figure 1 is a top plan view of a heel plate showing it in maximum expanded position.

Figure 2 is a similar view but showing the same in contracted position.

Figure 3 is an elevational view of the device with the heel plate clamped therein and showing one end of said plate resting on a support and the other end engaged by a hammer.

Figure 4 is a vertical cross section with one of the plates removed.

Figure 5 is a horizontal cross section taken on line 5—5 of Figure 3.

Figure 6 is an enlarged cross section taken on line 6—6 of Figure 3.

Referring by numerals to the accompanying drawings, 10 indicates a heel plate which is substantially of crescent shape having an intermediate curved portion 11 and divergent end portions 12. The intermediate portion is provided with a centrally located aperture 14 and a pair of apertures 15 spaced each equi-distant on each side of said central aperture.

Apertures 16 are located in the end portions 12 and are suitably spaced from apertures 15. All of these apertures are used for mailing the heel plate in position on the heel and apertures 15 are also utilized during the contraction of the plate as hereinafter more fully described.

The heel plates are generally furnished to the trade in the shape shown in Figure 1 and when a smaller sized plate is needed the stock plate is contracted by applying pressure to

the ends thereof, preferably by resting one end of the heel plate on a suitable support and tapping the other end by a tool, such as a hammer.

5 Quite frequently this operation causes buckling or distortion of the intermediate portion along the inner edge 11^a thereof. Also unless extreme care is used the heel plate very often is contracted too much and 10 is rendered unfit for use.

In order to prevent the distortion of the plate and to permit gauging thereof so that 15 said plate is contracted to the required size, I provide a clamping device 17 which securely holds the intermediate portion of the heel plate and provides means by which the extent of the span between the end portions can be readily ascertained.

This device comprises two plates 18 and 20 which are drawn together by a screw 20 and a butterfly nut 21. The head of the screw is seated in plate 18 and the threaded end of 25 said screw projects through an aperture formed in the other plate and receives nut 21 which can be drawn against said plate so as to clamp the heel plate in position.

Clamping plates 18 and 19 are substantially semi-circular in shape, the curved sides thereof being arranged adjacent to the outer 30 convex edge 11^b of the intermediate portion 11 and the straight sides of said clamping plates being arranged adjacent to and terminating short of the extremities of end 35 portions 12 when said heel plate is placed between said clamping plates.

Clamping plate 19 has fixed thereto and 40 projecting laterally therefrom a pair of pins 22. These pins are spaced to each side of the central axis of said plate and are adapted to extend through apertures 15 of the heel plate and engage corresponding apertures 24 formed in clamping plate 18. Thus said pins 22 serve to locate the heel plate in proper 45 position between the clamping plates 18 and 19. They also reinforce the intermediate portion of the heel plate and in combination with said clamping plates prevent the buckling thereof.

When the heel plate is being contracted 50 while clamped between the plates 18 and 19, that is, when pressure is applied to the ends 12, said pins 22 act as fulcrums, the end portions 12 being moved inwardly toward each other while the central portion 55 11 is reduced in diameter and the outer convex edge thereof is brought outwardly as indicated in dotted lines in Figure 3.

One of the clamping plates and preferably plate 19 is provided along its straight 60 or rear edge with two groups of marks 25. Each group consists of a series of spaced lines marked in odd numbers from 5 to 15. These numbers correspond to the numbers generally used to designate heel plates of various 65 sizes (see Figs. 1 and 2) and said lines or

marks 25 indicate the points of intersection of the inner curved edges 12^a of ends 12 with the straight edge of said clamping plate. Thus a heel plate marked 15 when placed in position between the clamping plates has its inner edges of the end portions intersecting the straight edge of the plate at points marked 15 as shown in full lines in Figure 3. A heel plate marked 5 (see Fig. 2) has its inner edges of the end portions intersecting the straight edge of the clamping plate at a point marked 5 as indicated in dotted lines in Figure 3.

In this manner the extent of contraction of the end portions of the heel plate can be 35 readily ascertained thereby enabling the shaping of the heel plate in an accurate manner without the danger of spoiling the heel plate by applying too much pressure to the ends thereof during the shaping 45 operation.

The clamping screw 20 is arranged preferably in alignment with the central axis of the heel plate and immediately beyond the inner concave edge 11^a thereof, as clearly 50 shown in Figure 4. Preferably each heel plate is scored on its outer face along radial lines in spaced relation with the center axis thereof and with the apertures 22, as indicated at 26. 55

I claim:

1. In a device of the class described, a pair of clamping plates adapted to receive therebetween a heel plate having a plurality of spaced apertures, a pair of pins fixed to and 100 projecting laterally from one of said plates and extending through the apertures of said heel plate and through coinciding apertures formed in the other clamping plate, and means for drawing said clamping plates together so as to clamp therebetween said heel plate, the ends of the latter being adapted to project beyond the rear edges of said clamping plates. 105

2. In a device of the class described, a pair of clamping plates adapted to receive therebetween a crescent-shaped heel plate, a pair of pins fixed to and projecting laterally from one of said plates and projecting into the apertures formed in the other of said 110 clamping plates, said pins being adapted to extend through apertures formed in said heel plate, thereby locating the latter in proper relation with respect to said clamping plates, a screw seated in one of said clamping plates and projecting through an aperture formed in the other clamping plate, and a nut screw threaded on the projecting end of said screw and adapted to be tightened against the corresponding clamping plate to secure said heel plate in position, the ends of said heel plate being adapted to extend beyond said clamping plates. 115

3. In a device of the class described, a pair 120 of clamping plates substantially semi-circu- 125

lar in shape and adapted to receive therebetween a heel plate substantially crescent-shaped, the ends of said heel plate being adapted to extend beyond the straight rear edges of said clamping plates, a pair of pins fixed to one of said clamping plates, and extending laterally therefrom and engaging apertures formed in the other of said clamping plates, said heel plate being provided with a pair of spaced apertures coinciding with the apertures in said clamping plate whereby said pins extend through said heel plate apertures and hold said heel plate in proper relationship with said clamping plates, and means for drawing said clamping plates together so as to clamp therebetween said heel plate while the ends thereof are subjected to pressure to contract said heel plate.

20 4. In a device of the class described, a pair of clamping plates substantially semi-circular in shape and adapted to receive therebetween a heel plate substantially crescent-shaped, the ends of said heel plate being adapted to extend beyond the straight rear edges of said clamping plates, a pair of pins fixed to one of said clamping plates and extending laterally therefrom and engaging apertures formed in the other of said clamping plates, said heel plate being provided with a pair of spaced apertures coinciding with the apertures in said clamping plate whereby said pins extend through said heel plate apertures and hold said heel plate in proper relationship with said clamping plates, means for drawing said clamping plates together so as to clamp therebetween said heel plate while the ends thereof are subjected to pressure to contract said heel plate, and graduations arranged on one of said clamping plates adjacent to the rear edge thereof, said graduations being marked and indicating the line of intersection between the inner edges of the end portions of the various sized heel plates.

25 5. In a device of the class described, a pair of clamping plates semi-circular in shape and adapted to receive therebetween a heel plate to be adjusted as to size, a pair of pins fixed in one of said clamping plates and projecting laterally therefrom and engaging a pair of apertures formed in the other clamping plate and adapted to pass through corresponding apertures formed in a heel plate, and a screw and wing nut means for drawing said clamping plates together and securing therebetween a heel plate.

30 6. In a device of the class described, a pair of clamping plates semi-circular in shape and adapted to receive therebetween a heel plate to be adjusted as to size, a pair of pins fixed in one of said clamping plates and projecting laterally therefrom and engaging a pair of apertures formed in the other clamping plate and adapted to pass through corresponding apertures formed in a heel plate,

a screw and wing nut means for drawing said clamping plates together and securing therebetween a heel plate, and graduations arranged on one of said clamping plates to each side of the central axis thereof and adjacent to the rear edge of same, said graduations indicating the point of intersection between the rear edge of said clamping plate and the inner edges of the end portions of a heel plate, said graduations being marked to correspond to the marks of the various sized heel plates.

In testimony whereof I hereunto affix my signature this 20th day of December, 1930.

FREDERICK D. REYNOLDS.
